(57) CLAIM

The ornamental design for a combined bird table and shelter, as shown and described.

DESCRIPTION

FIG. 1 is a side elevational view of the table portion of a combined bird table and shelter showing my new design, it being shown separately from the shelter for clarity of disclosure;

FIG. 2 is a side elevational view of a combined bird table and shelter, the break in the table portion representing indiscriminate length;

FIG. 3 is a bottom plan view of FIG. 1;

FIG. 4 is a top plan view of FIG. 1;

FIG. 5 is a bottom plan view of FIG. 2; and,

FIG. 6 is a top plan view of FIG. 2.
